US0D1008204S

(12) **United States Design Patent** (10) **Patent No.:** **US D1,008,204 S**
(45) **Date of Patent:** **** Dec. 19, 2023**

(54) **CELL PHONE**

(71) Applicant: **HMD Global Oy**, Espoo (FI)

(72) Inventor: **Jonathon Lister**, Orpington (GB)

(73) Assignee: **HMD Global Oy**, Espoo (FI)

(**) Term: **15 Years**

(21) Appl. No.: **29/778,211**

(22) Filed: **Apr. 12, 2021**

(30) **Foreign Application Priority Data**

Oct. 12, 2020 (EM) 008200430-0001

(51) **LOC (14) Cl.** **14-03**

(52) **U.S. Cl.**

USPC ..... **D14/138 AA**

(57) **CLAIM**

The ornamental design for a cell phone, as shown and described.

DESCRIPTION

FIG. 1 is a front perspective view of a cell phone showing my design.

FIG. 2 is a bottom rear perspective view of the cell phone.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines in the drawings are employed to show unclaimed portions of the cell phone, and form no part of the claimed design.

1 Claim, 8 Drawing Sheets

US D1,008,204 S
